BLIND STITCH SEWING MACHINES

Edward Franklin, Alwoodley, Leeds, and Norman Adamson, Oakwood, Leeds, England

Application July 23, 1953, Serial No. 369,845

3 Claims. (Cl. 112—176)

This invention relates to blind stitch sewing machines and concerns certain improvements in the construction, mounting and operation of the head carrying and needle plate, needle, looper and feeder and their operating connections, and of the work support carrying the plunger or plungers.

Machines of this type as heretofore constructed have had the head supported so as to be stationary during sewing, while the work support has been arranged to pivot relative to the head to allow insertion of the work between the two and to move the work up to the head, the work support being capable of limited movement to allow automatically for variations in thickness of material passing over it.

Such a construction of machine has numerous disadvantages and drawbacks, some or all of which are overcome by the present invention.

In particular it is an object of the invention to eliminate the erratic plunging motion caused by undesired movement of the plunger or plungers due to the effect on their operating connections of the pivotal movement of the work support.

Another object is to reduce the amount of obstruction to the introduction and passage of the work by enabling the area of the work support to be kept small as is required, for example, in sewing the lapel rolls.

A further object is to give easier access for the work between support and head to facilitate correct positioning of the work relative to the needle and thereby minimise the risk of distortion and incorrect placing.

A still further object is to prevent the weight of the work from moving the work support and thereby causing erratic needle penetration due to incorrect movement of the plunger or plungers caused by the effect on their operating connections of the pivotal movement of the work support.

Other objects are to cheapen and simplify the manufacture of the machines, to call for fewer working parts, and to enable better work to be produced or less skilled operators to be employed.

With these objects mainly in view the improved machine according to the invention has the head carrying the needle plate, needle, looper and feeder together with their operating connections arranged to be movable by the operator relative to the work support which is arranged to be stationary during normal operation of the machine.

The head and the mechanism it carries is pivoted on the machine body behind the work support so that when raised angularly the widest part of the gap for insertion and removal of the work is nearest to the operator.

In order that the invention may be clearly understood and readily carried into effect one construction of machine according thereto will hereafter be described with reference to the accompanying drawings by way of example, though the scope of the invention is not to be regarded as limited thereby. In these drawings Figure 1 is an end elevation of the main part of the machine looking in the direction of arrow A in Figure 2 but with certain por-

2

tions sectioned, whilst Figure 2 is a sectional elevation taken substantially on the line II—II in Figure 1.

Referring to these drawings the machine is shown as having a base plate 1 which is secured on a table or support frame 2. The work support is in the form of a hollow pillar 3 rigidly mounted on the base plate 1 near the front thereof, that is nearest the operator, and its upper surface is of small area having approximately the same dimensions for length and width. The hollow pillar 3 containing one or more plungers 4 (two being illustrated) of usual construction which are pivoted therein and connected by links 5 to arms 6 secured on a rock shaft 7 supported below the base plate 1 and the body 8 of the machine. This shaft 7 can be rocked by links 9, 10 from an eccentric cam 11 driven through gears 12, 13 from a horizontal main shaft 14, this arrangement being such that the plungers 4 are operated beneath the work in known fashion.

The main shaft 14 is supported at one end by a suitable bearing in the body 8 and has secured to it a belt pulley 15 through which it is driven from an electric motor (not shown). The other end of this main shaft 14 is supported by a bearing bushing 16 mounted in one end of a pivot sleeve 17 which is in turn supported for partial rotation in a long bearing formed by the body 8.

This pivot sleeve 17 projects beyond the body 8 and has secured to it by screwed studs 18 the rear end of the head 19. This head 19 carries at its front end the needle plate 20, needle 21, looper 22 and feeder 23, all located substantially above the stationary work support pillar 3, together with the operating connections therefor in known fashion.

One end of the main shaft 14 carries, firstly an eccentric cam 24 actuating the link 25 for the feeder 23, secondly an eccentric cam 26 actuating through a universal coupling 27 the needle bar driving shaft 28, and thirdly a universal bushing 29 actuating the looper shaft 30, all in known fashion. By reason of these connections between the various head mechanisms and the main shaft and by reason of the very small amount of angular movement of the rear end of the head caused by the lifting and lowering of the front end sufficiently for insertion and removal of the work, there is no appreciable disturbance in the relative positions of needle plate, needle, looper and feeder.

The inner end of the pivot sleeve 17 has secured on it the boss 31 of an arm 32 which is connected by link 33 to a foot pedal (not shown). The sleeve 17 also has screwed into it a rod 34 whose lower end is acted on by the free end of a leaf spring 35 whose other end is anchored to the base plate 1, the pressure of the spring being adjustable. The arrangement is such that the head can be raised and lowered by the operator as required for insertion and removal of work the spring yielding horizontally to the angular movement of rod 34 and sleeve 17, and yet can lift against the spring pressure to allow automatically for variations in the thickness of material passing beneath the head.

The sleeve 17 has secured thereon a further arm 36 the forked end of which engages flats on a long non-rotatable nut 37, this nut being threaded on a screwed spindle 38 held against axial movement in a bearing 39 in the front of the machine body 8, the outer end of this spindle 38 having secured thereon a calibrated knob 40 for adjusting the position of nut 37 and thereby controlling the lowest position of the pivot head 19 and hence the depth of penetration of the needle. The abutment 37^x formed by one end of the nut 37 limits the movement of the forked arm 36 in one direction and thereby limits the downward movement of the front end of the pivoted head.

By such a construction of machine many of the disadvantages of previous constructions are overcome. More-

over, the rigidly mounted stationary work support of small area enables for example, a lapel roll to be sewn readily in a desired form without interference such as is experienced with a moving work-support.

We claim:

1. In a blind stitch sewing machine, the combination of a stationary body portion, a work support having at least one plunger, said work support arranged to be stationary during normal operation of the machine, an elongated head extending forwardly from said machine body at right angles thereto and in a direction parallel to the line of feed and carrying at its forward outer end a needle plate, needle, looper and feeder and their operating connections, said head having its rear end pivotally mounted on said machine body behind said work support so that when its forward outer end is raised angularly the widest part of the gap for insertion and removal of the work is nearest to the operator, and a manually operable means connected to said pivoted head for enabling the operator to lower and raise the forward outer end of said head with its associated parts towards and away from said stationary support to allow insertion and removal of the work.

2. In a blind stitch sewing machine, the combination as called for in claim 1 including a main driving shaft, a long pivot sleeve supported for partial rotation in the machine body and through which said main driving shaft for the stitching mechanism in the head passes, said pivot sleeve having secured thereto the rear end of the head and constituting the sole support for said head, connections from said pivot sleeve to said manually operable means by which the operator can turn said sleeve to raise or lower the forward outer end of said head, and an adjustable control device comprising a member angularly movable with said pivot sleeve and an abutment supported from the machine body arranged to cooperate with one another to limit automatically to a predetermined degree the lowering of the forward outer end of the head during the operation of the machine.

3. In a blind stitch sewing machine, the combination

of a stationary body portion, a work support having at least one plunger, said work support arranged to be stationary during normal operation of the machine, a main driving shaft for the stitching mechanism, a long pivot sleeve supported for partial rotation in said machine body and through which said main driving shaft passes, an elongated head extending forwardly from said body at right angles to said main driving shaft and carrying at its front end a needle plate, needle, looper and feeder (constituting said stitching mechanism) and their operating connections, said pivot sleeve having secured thereto the rear end of said head and constituting the sole support for said head the front end of which is located above said work support, a footpedal connected to an arm on said pivot sleeve so as to enable the operator to turn said sleeve and thereby lower and raise the front end of said head with its associated parts angularly in the vertical plane in which said head extends and towards and away from said stationary work support, and an adjustable control device arranged to limit automatically to a predetermined degree the lowering of the head during the operation of the machine, said control device including an arm secured on the pivot sleeve and having a forked end engaging flats on a long nut non-rotatably threaded on a screwed spindle which is arranged to be rotated by a calibrated knob so as to move said nut axially, said nut carrying an abutment located so as to limit the movement of said arm in the direction corresponding to the lowering of the head.
